KNOCKDOWN SHEET METAL CABINET

Ralph Stevenson and Isaac Nadolsky, Grand
Rapids, Mich., assignors to Grand Rapids Metal
Cabinet Company, Grand Rapids, Mich., a cor-
poration of Michigan

Application January 21, 1946, Serial No. 642,507

3 Claims. (Cl. 312—143)

1

This invention relates to a knock-down cabinet made of thin sheet metal. It is a primary object and purpose of our invention to provide a cabinet, substantially all parts of which are readily pressed and formed from sheet metal, including top, sides, back, a supporting base structure, shelves and a closing door for the front, said parts being shipped or otherwise transported in separated condition, and all very quickly put together and assembled to make a completed cabinet with no necessity of skilled labor being employed for such purpose, and with the use of but little more than a screw driver on such assembly. When assembled, the various parts making up the cabinet, are securely held against accidental or other disconnection, and a very serviceable and attractive appearing cabinet is produced at low cost. An understanding of our invention may be had from the following description, taken in connection with the accompanying drawings, in which,

Fig. 1 is a perspective view of the cabinet of our invention with the door being open.

Fig. 2 is a vertical section, from front to rear, with the door closed.

Fig. 3 is a fragmentary perspective view illustrative of parts used in the makeup of the cabinet, excepting the door, said parts being in separated condition.

Fig. 4 is an enlarged fragmentary vertical section similar to the section shown in Fig. 2, with parts broken away, showing the detail of assembly of the several parts of the cabinet body.

Fig. 5 is a fragmentary plan at one end of the cabinet.

Fig. 6 is a fragmentary horizontal section, at one end of the cabinet, above an intermediate shelf therein.

Fig. 7 is a fragmentary vertical section adjacent a rear corner of the cabinet and through an end of a shelf.

Fig. 8 is a fragmentary vertical section of the cabinet at an upper front corner portion thereof.

Fig. 9 is a fragmentary horizontal section at the front of the cabinet at the side where the door is hinged, said door being shown fragmentarily in section, and one of the hinges shown in plan.

In the construction, the under-support base frame includes a front channel 1 with a vertical web and rearwardly extending flanges and with rearwardly turned ends, the lower flange at its ends being depressed at 2 a distance equal substantially to the thickness of the metal used in the cabinet structure. Two side members are also used, each in a form of a channel 3 having outer

2

vertical webs and inwardly extending upper and lower flanges, the upper flanges each at its front end and also the web at its front end being offset downwardly and inwardly substantially the thickness of the metal as shown at 4, and the lower flange at its rear end pressed downwardly a like distance as indicated at 5 (Fig. 3). The front end portions of the two side members 3 are inserted at the ends of the front channel member 1 as shown and with the upper surfaces of all the upper flanges of the channels 1 and 3 substantially flush and in the same horizontal plane. The upper flanges of the side channels 3 adjacent their ends and the upper flange of the front channel 1, similarly, have vertical openings for the passage of short bolts as hereafter set forth.

The sides of the cabinet are likewise made from thin flat or sheet metal. Each side has a rectangular body 6, at the front vertical edge of which a section 7 is turned inwardly at right angles for a distance, and then again turned at right angles making a terminal flange 8 (Fig. 3) parallel to the body 6. The flange 8 at its lower end is widened somewhat as shown at 9 in Fig. 3, and at spaced apart preselected parts of the length of the flange 8 rearwardly extending tongues 10, are provided, there being notches, as shown at 11 and 11a, made in the flange 8 at the integral connection of the tongues 11 thereto, and 20 at their upper edges. At the rear vertical edge of the body 6, a flange 12 of a predetermined width is turned inwardly at right angles, and at its free edge a plurality of tongues 13 are turned at right angles in a forward direction. At the lower edge 25 of the body 6, a bottom flange 14 is turned inwardly in a horizontal plane, and it is provided with openings to come in conjunction with the openings in the upper flanges of the base frame channels 1 and 3, when a vertical side of the 30 cabinet, constructed as described, is located in place one on each side channel member 3 of the lower supporting base frame.

The back 15 is made from a single rectangular sheet of metal. Inwardly a short distance from each vertical edge, rectangular spaced openings 16 are made. The back may be located within the rear flanges 12 of the two vertical sides of the cabinet, resting against the upper side of the bottom flange 14, and moved rearwardly so that 45 the tongues 13 pass through the openings 16. Short bolts 17 are inserted through the openings in the flanges 14 of the sides and in the upper flanges of the supporting channels 1 and 3 (Figs. 2 and 4) and nuts screwed on to the bolts, de- 50 tachably connecting said sides and base frame

together; and with the back 15 located in place and detachably connected with the tongues 13, the structure is assembled sufficiently to receive, in succession, a bottom shelf, a series of intermediate vertically spaced shelves 28, and a top, which will complete the cabinet except for a door to close the front opening located between the inwardly extending flanges 8 at the front of the two sides of the cabinet.

A bottom shelf is also made from thin flat metal. It has a body 18 of rectangular form adapted to be located horizontally and at its rear it is provided with a downturned flange 19 and at each end with a downturned flange 20. At the front and for the full length of the front except a distance at each end, the metal is turned downwardly to make a flange section 21, having a vertical height comparative to the height of the flanges 19 and 20, is then bent outwardly to make a short horizontal section 22, continued in a downward direction to provide a vertical face section 23, and terminates in a lower horizontal rearwardly bent flange 24. At each end of the front of the bottom shelf as thus formed, it is separated from an end front portion 25 wherein the metal of the upper body 18 of the shelf at the front and at each end, is turned downwardly and continued as a single vertical section indicated at 25, separated by a slot from the formation which contains the sections 21 and 24, inclusive, and located back of the face section 23.

The back 15 is formed with inwardly pressed spaced longitudinal and vertical ribs 26, the horizontal ribs being properly located with reference to the bottom and other shelves and the top which are to be assembled in place, and the vertical ribs a very short distance within the tongue-receiving openings 16. The body 6 of each vertical side, similarly, a short distance from the bottom flange 14, and below the upper end of each side, has a continuous horizontal rib 27 pressed inwardly. In the assembly of the bottom shelf, after the sides and back are connected in place, the rear flange 19 is brought against the upper side of the lowest inwardly extending rib 26 of the back 15 and the shelf, which is held in an upwardly and forwardly inclined position, is turned downwardly to bring the lower edges of the flanges 20 against the upper sides of the lowermost ribs 27 of the sides 6. The flange portions 9 at the lower parts of the flanges 8 enter the slots between sections 25 and the ends of the sections 21 and 24, inclusive. Of course, the rear flange 19 at its proper places is vertically-slotted at 19a for the entrance of tongues 13 into said slots. As shown in the drawings, the body 18 of the shelf at its front and rear edges is reinforced by a slight upward bending of the metal to provide a continuous bead around the shelf. The notches 11 at the upper ends of the widened section 9 receive the front edge portions of the horizontal body 18 of the shelf, which comes thereto and snaps into place and interlocks therewith.

The intermediate shelves 28 have downturned rear flanges 29 notched at 29a to receive the tongues 13. They also have downturned end flanges 30 and downturned front flanges 31 with inwardly bent lower edges 32. The flanges 31 and edges 32 are notched at 31a to receive the tongues 11.

The top is of similar structure to the bottom and intermediate shelves. It is made from sheet metal and includes a horizontal rectangular body 34, a rear downturned flange 35, and similar end flanges 36, the flange 35 being notched in its lower

edge at 35a to receive the tongues 13. At the front the intermediate portion consists of a relatively wide flange 37, slightly offset rearward at 38 at its lower edge, and then continued in a short downward extension 39 which terminates in a rearwardly turned flange 40. Toward each end, the metal is vertically slotted and a section 41, like the parts 25 and 33, having a horizontal dimension substantially equal to the width of the flange 7, extends downwardly and is set back from the flange portion 37, a distance equal substantially to the thickness of the metal used in the parts of the cabinet. At each end of the section 39, a hook 42 is provided, by an extension 15 and a vertical slot cut upwardly therein from the lower edge of the section 39 (Fig. 8) to engage with the uppermost tongue 10.

The intermediate shelves and the top are applied by locating the downturned flanges 29 and 35, respectively, first in place against the inwardly pressed horizontal ribs 26, and with said shelves and top inclined upwardly and outwardly moving them down at their forward portions to place, with a snapping into the notches 11 and 11a of the edge portions of the shelves and top at the upper ends of the slots which separate the front intermediate portions of said shelves and top from their end sections 33 and 41, respectively. The end flanges 36, of the top will come against the upper horizontal ribs 27 of the vertical sides 6 of the cabinet.

When thus assembled, the cabinet is firmly and securely held together and will not accidentally or otherwise separate in normal use thereof. The several members which make up the cabinet may be shipped in a knock-down condition and assembled in complete form in a very short time, with the use of no tools except those required to connect the screw bolts 17.

40 The assembled cabinet will have a front opening, at the vertical sides of which are the facing portions 7, and at the upper and lower ends are the facing sections 37 and 23 in the same plane therewith, while the sections 21 and 39, and also 45 the front edges 31 of the intermediate shelves provide stops for a door which may be used to close such front opening. The door 43 is also made from a rectangular plate of thin metal which may be pressed in shape, in accordance with any preferred design, to give a pleasing appearance and also acting to strengthen and reinforce, and at the edges rearwardly turned flanges 44 are preferably made for further strengthening and reinforcement.

55 The door is hinged mounted to swing about a vertical axis. A plurality of hinges are used. As shown in Fig. 9, each hinge consists of a flat leaf 45, located at the rear side of one of the sections 7, and spot welded or otherwise permanently secured. The other leaf consists of an end section 47 pivotally connected to one edge of the leaf 45 and, when the door is closed, lying parallel thereto. At the other end of the section 47, a semicircular, relatively long section 38 extends, being preferably ribbed for strength, from which a flat terminal section 49 extends and is located against the inner side of the door 43 within the adjacent vertical flange 44 and is permanently connected to the door in the same manner. The 70 two parts of the hinge may be connected respectively to the cabinet and the door and in assembly the hinge pins or pintles inserted so that the door may be shipped separate from the rest of the cabinet to conserve space in shipment. The door may be swung open, as shown in Fig. 1, or it

may be moved to completely closed position and releasably latched when closed, the usual handle and releasable latch being supplied.

The construction is very practical, economical to build, and with it a cabinet having its interior space divided by vertically separated horizontal shelves, is made, all parts being of sheet metal, ready to be assembled and when assembled interlocking, providing a securely connected structure.

The invention is defined in the appended claims and is to be considered comprehensive of all forms of structure coming within its scope.

We claim:

1. In a structure as described, a supporting base including, spaced side members and a front member, each of sheet metal channel form, vertical sides located over the side members, each of sheet metal, and having a lower horizontal flange resting upon the upper sides of the base side members, means for detachably connecting said horizontal flanges to said supporting frame, said side members at their rear edges having in-turned flanges from the edges of which a plurality of vertically spaced tongues extend in a forward direction, and at their front having in-turned facing flanges from the edges of which terminal flanges extend rearwardly, said terminal flanges having a plurality of vertically spaced rearwardly extending tongues, a bottom shelf, a plurality of intermediate shelves and a top, all of sheet metal, carried on said tongues and having means for releasable interconnection therewith, and a back comprising a plate of sheet metal located within the rear in-turned flanges of said sides and having openings through which the tongues thereon pass, said shelves and top bearing against the front of said back and holding it against said rear flanges.

2. A construction as defined in claim 1, said shelves and top each comprising a rectangular plate of flat metal, each having flanges extending downwardly at its sides and ends, said back having forwardly pressed horizontal beads upon

which the rear flanges of the shelves and top bear at their lower edges, and said sides having upper and lower inwardly pressed horizontal beads against which the end flanges of the bottom and top rest, as described.

3. In a structure as described, a base support, vertical sides of sheet metal having in-turned front and rear flanges connected to and extending upwardly from the base support at opposite sides thereof, a back of sheet metal located between said sides and at the front of the rear flanges thereof, said back having openings and said flanges having forwardly extending tongues passing through said openings, a bottom shelf, a plurality of intermediate, vertically spaced horizontal shelves and a top, all of sheet metal, said shelves and top having downturned front and rear flanges, said rear flanges being located forwardly of said back, and said front flanges on the vertical sides having rearwardly extending tongues, said flanges on the shelves being slotted for the reception of said tongues, said front flanges of the vertical sides at their inner edges having rearwardly turned terminal flanges from which said tongues of the front flanges extend rearwardly, said rearwardly turned terminal flanges having notches at the upper edges of said tongues receiving portions of the bottom and intermediate shelves.

RALPH STEVENSON.
